J. LOEB.
Show-Box for Laces.

No. 226,088

Patented Mar. 30, 1880

UNITED STATES PATENT OFFICE.

JACOB LOEB, OF PHILADELPHIA, PENNSYLVANIA.

SHOW-BOX FOR LACES.

SPECIFICATION forming part of Letters Patent No. 226,088, dated March 30, 1880.

Application filed February 5, 1880.

To all whom it may concern:

Be it known that I, JACOB LOEB, of the city and county of Philadelphia, and State of Pennsylvania, have invented an Improvement in 5 Show-Boxes for Laces, &c., of which the following is a specification.

My invention relates to that class of packing-boxes for holding embroidery, lace, &c., which are provided with a lid and a means 10 whereby the goods can be examined without opening the box.

Heretofore this class of goods has been put up in an entirely exposed condition, which want of a protecting-cover caused the goods 15 to be greatly soiled in a very short space of time, and which soiling signifies loss to the dealer; or the goods were put up in soft-paper wrappers with a part of the same exposed; or they were put up in wrappers and tied, pasted, 20 or pinned without any part being exposed; but the softness of the wrappers did not prevent the goods they contained from crumpling or becoming otherwise damaged from handling, and in which condition they were comparatively worthless; or, finally, the goods were put 25 up in boxes, referred to above, and which belong to the class to which this invention relates.

My invention consists of a box for displaying 30 laces, &c., provided with a hinged flap for securing the goods to in such a position that they may be inspected through an aperture in the bottom of the box, the box also having inside flaps on the ends and double overlapping lids.

The object of my invention is to pack delicately-made goods—such as Hamburg edging, embroidery, or lace—in such a manner that they may be handled, withdrawn, or replaced 35 in the package or box without soiling or otherwise damaging them; also, to provide means 40 of exposing a portion of the goods without injury to the same and without opening the box; and, further, to provide means to withdraw the goods from the said box without opening 45 it; also to provide the box with two lids instead of one, obviating the difficulty presented in a wide cover or lid by warping.

In the drawings, Figure 1 is a perspective view of my improved box with the lids open. 50 Fig. 2 is a cross-section of the same. Fig. 3

is a perspective view of the same with all the goods taken out. Fig. 4 is a perspective view of the same with the bottom upward. Fig. 5 is a perspective view of the same with the lids closed. Fig. 6 is a perspective view, showing 55 a modified form of exposing piece.

A is the frame of the box, preferably made of wood. B is the bottom, in practice made of card-board or its equivalent, and is provided with an opening or aperture, b. C and D are 60 the lids. The lid C is hinged to the frame A, and in width is equal to one-half the width of the box. The lid D is also hinged to the frame A, and is of two thicknesses of material. That portion lettered d is of greater thickness than 65 the lid C, but is of the same width, and that portion lettered d' is of about the same thickness and width as lid C. When these lids are closed they appear as shown in Figs. 2 and 5. To the part d' of the lid D are attached tabs 70 E, F, and F', which, when the lids are closed, as shown in Fig. 5, are caught, respectively, over the pins e, f, and f', and by this means the lids are firmly held down and the box shut. Hinged to the bottom B, at g, is a piece of 75 card-board or its equivalent, G, preferably of greater area than the opening b. When this is laid flat upon the bottom it covers the opening b. The side of the piece G which is exposed is papered or otherwise colored, so as to 80 make a greater contrast and expose the goods which are wrapped over said board G to better advantage.

Instead of hinging the piece G to the bottom, the said bottom may be cut, as shown in 85 Fig. 6, and the piece G' being bent up, the goods are wrapped upon it, and it is placed back again. Upon either end of the box or frame A are hinged loose flaps H H, which flaps are just wide enough to lie between the 90 sides of the frame, so that when the lids C and D are closed said lids shall rest flat upon the frame A and flaps. Such must be the case, since the flaps, when closed, are on a level with the frame A. Secured to the end of the 95 goods is a cord, I, or its equivalent, which is left projecting from the box, Fig. 5, when the lids are closed.

The operation of the box is as follows: After the goods have been folded up into meas- 100

ured lengths one end is wrapped one or more times around the piece G, and this is then laid down upon the bottom of the box.

Boxes have been made with slits in the bottom, through which the goods are drawn; but it is evident that much time is taken up in drawing the ends through these slits and making them lie even, and, besides, the goods project slightly beyond the bottom, and if laid upon the counter or other resting-place they are liable to become soiled; whereas, by wrapping the ends upon the card G and then laying it down upon the bottom the goods can be quickly prepared for exposure, and when packed the exposed portions are not on a level with the bottom of the box, and hence are not soiled when the said box is laid upon the counter, &c.

When the goods have been wrapped around piece G and that piece laid upon the bottom the rest of said goods are evenly spread in the box, and to the end is attached the cord or tab I. When laid in the box the flaps H are folded down over the folds in the goods to keep them from being displaced. The lid C is then closed, and next the lid D, and the catches or tabs E F F' are fastened over the pins *eff'*.

Upon turning over the box, it will be seen

that that part of the goods wrapped around piece G is exposed to view and yet is wholly within the box.

To sell any quantity of the goods it is not necessary to open the box, since by pulling upon the cord I the end of the goods becomes exposed, and it can be continuously withdrawn to any desired extent and cut off close to the box. Should more be withdrawn than desired the box can be easily and speedily opened and the goods replaced.

Having now described my invention, what I claim as new, and desire to secure by Letters Patent, is—

A box or case for packing embroidery, lace, &c., which will expose a portion of the goods, can be conveniently and quickly opened or closed, and will prevent soiling of the goods contained therein, consisting of the frame A, apertured bottom B, hinged piece G, or its equivalent, double lapping lids C and D, and flaps H H, substantially as and for the purpose specified.

In testimony of which invention I hereunto set my hand.

JACOB LOEB.
